ADJUSTABLE STRINGER MOLD FOR CONCRETE STEPS

Ralph L. Cline, Hickory, N. C.

Application December 6, 1948, Serial No. 63,767

5 Claims. (Cl. 25—118)

1

This invention relates to an adjustable riser supporting stringer for use in conjunction with forms for pouring concrete steps and the like.

Heretofore, there have been various means by which the riser members which extend transversely between the side form members of concrete steps have been supported. The most commonly used means is that of cutting notches in large timbers, such as 2' by 8's, the notches of which are cut according to the rise and tread of the proposed steps to be poured and the riser members were then nailed to the notches and then the riser supporting means, which are commonly called stringers, would be rigidly mounted between the side forms of the concrete steps, in any suitable manner, after which the concrete was poured against the riser members between the side form members.

It is an object of this invention to provide a stringer comprised of a number of parts and which may be easily disassembled for conveying the same from one place to another.

It is another object of this invention to provide a riser supporting stringer which comprises a plurality of L-shaped bars, the horizontal legs of which are disposed on a horizontal plane, one above the other but in staggered relation to each other and the horizontal leg of each of which is provided with a bracket for connecting the same to the vertical leg of the next adjacent lower L-shaped bar and these brackets being adjustable on the horizontal as well as the vertical legs of the L-shaped members to provide means for adjusting the position of the L-shaped or right angular members with respect to each other to conform to the desired height of the risers and the width of the treads of the proposed concrete steps.

It is another object of this invention to provide a stringer of the type described and wherein in each of the vertical legs of the right angular members is provided with a vertically adjustable member to which the riser is adapted to be secured and whereby the range of vertical adjustment of the vertically adjustable member will permit the utilization of any desired width of riser boards.

Some of the objects of the invention having been stated, other objects will appear as the description proceeds when taken in connection with the accompanying drawings in which—

Figure 1 is a top plan view of the apparatus, showing it in conjunction with the side form members for concrete steps and showing the con-

2

crete after it has been poured against two of the risers;

Figure 2 is a front elevation of the apparatus with the central portion broken away;

5 Figure 3 is a vertical sectional view taken along the line 3—3 in Figure 2;

Figure 4 is an elevation with parts in section looking from along the line 4—4 in Figure 2;

10 Figure 5 is an isometric view showing one of the assembled stringers and is taken substantially along the line 3—3 in Figure 2;

Figure 6 is an enlarged inverted sectional plan view and is taken substantially along the line 6—6 in Figure 3.

15 Referring more specifically to the drawings, the numerals 10 and 10' indicate left-hand and right-hand vertically disposed side form panels which are reinforced by and suitably secured to spaced upstanding stakes 11 and 11', respectively, the lower ends of which project below the panels 10 and 10' respectively, and are driven into the ground indicated at G. Obviously, the stake 11 would be of the same length as the height of the side panel 10 in the event that 20 the concrete steps were to be poured on an impenetrable surface such as a concrete or wood floor. The right-hand side form panel 10' and associated parts, being identical to those at the left-hand side, will bear the same reference characters with the prime notation added, except 25 the members comprising portions 40, 43 and 50 are opposite hand.

The stakes 11 are each supported by an angularly disposed brace bar 12 suitably nailed at its upper end to the associated stake 11 and at its lower end to a smaller upstanding stake 13 which is also driven into the ground G.

A frame member 14 spans the distance between the side panels 10 and 10' at the lower front edges thereof and it may be observed in 40 Figures 3, 4, and 5 that this frame member 14 is disposed at the lower left-hand corner of the side panel 10. The side panel 10 may be nailed or secured in any other suitable manner to the opposite ends of the frame member 14. It may also be observed in Figures 3, 4 and 5 that the right-hand edge of the side panel 10 is nailed or secured in any other suitable manner to a frame member 15 which spans the distance between the side panels 10 and 10'.

45 The parts heretofore described are the usual parts of conventional step forms and it is with these parts that this invention is adapted to be associated.

50 Broadly, the invention is comprised of a plu-

rality of L-shaped or right angular bars, all of which are identical. However, due to the fact that those bars at the upper and lower ends of the stringer are secured to the frame members of the form in a different manner and also due to the fact that the intermediate L-shaped members are secured to the uppermost and lowermost L-shaped members in a different manner, the description will refer to the lower, the intermediate and the upper L-shaped bars by different reference characters, for purposes of clarity.

In the drawings there are two stringer assemblies broadly designated at 20 and 20', respectively. The stringer assembly 20' being identical in all respects to the stringer assembly 20, with the exception of various of the parts being opposite hand, will bear the same reference characters as the stringer assembly 20 with the prime notation added. It might be stated that there may be any desired number of these stringer assemblies 20 placed at various points apart from each other between the side forms 10 and 10', depending upon the width of the steps to be poured, to thus lend rigidity to the center portions of the risers to be presently described. It is evident that although both left-hand and right-hand stringer assemblies are shown in the drawings, if so desired, all of the stringer assemblies may be identical or they may be opposite hand as shown in Figures 1, 2, 3 and 4.

The stringer assembly 20 is shown in the drawings as comprising a lower L-shaped bar 21, an intermediate L-shaped bar 22 (of which there may be any desired number) and an upper L-shaped bar 23, all of which are identical. The horizontal leg of the L-shaped bar 21 is adjustably mounted in a guide block 24, secured as by screws 25 to the lower frame member 14. A set screw 26 threadably penetrates the guide block 24 and bears against the horizontal leg of the bar 21 thus locking the same in adjusted position. The vertical leg of the L-shaped bar 21 slidably penetrates a guide block 27 which is identical to the guide block 24. This guide block 27 is secured as by screws 30 to the first riser 31, the opposite ends of which are secured to the end form panels 10 and 10' in any suitable manner, such as by nailing.

The vertical leg of the L-shaped member 21 is adjustably secured in the guide block 27 as by a set screw 32 which threadably penetrates the guide block 27 and bears against the vertical legs of the L-shaped member 21. The vertical legs of the L-shaped bars 22 and 23 slidably penetrate guide blocks which are identical to and bear the same reference character as the guide block 27, in which the vertical leg of the L-shaped member 21 is mounted. The guide block 27 in which the vertical leg of the L-shaped member 22 is mounted is secured by the screws 30 to a second riser 35 and the guide block 27 in which the vertical leg of the upper L-shaped member 23 is mounted is secured by the screws 30 to the transverse frame member 15 between the side form panels 10 and 10'.

It will be noted that the lower outer edges of the risers 31 and 35 are beveled thus forming a sharp edge at the inner lower edges of the risers 31 and 35. This sharp edge on the lower edge of the riser 31 is not essential, however; the sharp edge at the bottom of the riser 35 is provided so that after the concrete C has been poured between the side form panels 10 and 10' and against the inner surfaces of the risers 31 and 35, a mason will be able to finish practically the entire upper

surface of the tread smoothly to the juncture of the tread and the riser formed by the riser member 35.

The horizontal legs of the intermediate L-shaped member 22 as well as of the upper L-shaped member 23 are connected to the vertical legs of the L-shaped members 21 and 22, respectively in the identical manner and, therefore, the parts associated with the vertical legs of the L-shaped bars 21 and 22 will bear the same reference character.

A portion of the horizontal leg of the L-shaped bar 22 is slidably mounted between the flanges of a channel-shaped member 40 having spaced vertically disposed bars welded to and spanning the distance between the flanges of the same and it is obvious that the channel bar 40 thus formed may be a tubular member which is rectangular in cross section if so desired. A set screw 42 threadably penetrates one of the flanges of the channel bar 40 and adjustably secures the horizontal leg of the L-shaped member 22 in the channel bar 40.

A channel bar 43 is welded to the side of the channel bar 40 and extends upwardly therefrom. This channel bar 43, like the channel bar 40, is provided with cross-bars 44 which span the distance between and are welded to the flanges of the channel bar 43 and it is obvious that this channel bar 43 may also be a tubular member which is rectangular in cross section. This channel bar 43 has the vertical leg of the L-shaped bar 21 mounted between the flanges thereof to permit vertical sliding movement of the channel bar 43 on the vertical leg of the L-shaped bar 21 as by a set screw 45 which threadably penetrates one of the flanges of the channel bar 43 and bears against the vertical leg of the L-shaped bar 21.

It is thus seen that, since the channel bar 40 is integral with the channel bar 43, vertical adjustment of the channel bar 43 will also adjust the horizontal leg of the L-shaped bar 22 in a vertical plane relative to the vertical leg of the L-shaped bar 21. It will be noted that the guide blocks 27 are cut at an angle as at 46 at their lower ends which will thus permit the bottom edge of the horizontal leg of any one of the L-shaped bars 21 to 23 inclusive, to be adjusted flush with the lower end of its associated block 27.

An angularly disposed channel bar 50 is welded to the upper flange of the channel bar 40 and to the web of the channel bar 43 thus serving as a bracing member between the two channel members 40 and 43. This angularly disposed channel bar 50 is slidably penetrated intermediate its ends by a bolt 51 which loosely penetrates a washer 52 which is shown to be a square washer, but may be of any desired shape.

This washer 52 (Figure 6) is slidably engaged by a channel bar 53 which is also loosely penetrated by the bolt 51 and the head of the bolt 51 is disposed in a counterbore 54 in the web of the channel bar 53 so that the head of the bolt 51 will be flush with the inner surface of the web of the channel bar 53. It will be noted in Figure 6 that the upper end of the bolt 51 has lock nuts 55 threadably mounted thereon and which will permit oscillation of the channel bar 50, the washer 52 and the channel bar 53, relative to each other, on the bolt 51. It might be stated that a rivet may be used, if desired, in lieu of the bolt 51 and have its ends peened or turned 75 over in such a manner as to permit the relative

oscillatory movement between the channel bars 50 and 53 and the washer 52.

The channel bar 53, which may be a tubular member, rectangular in cross-section, if so desired, has cross-bars 56 welded to and spanning the distance between its flanges, and an angularly disposed brace bar 51 is slidably mounted in the channel bar 53 and one of the cross-bars 56 has an adjustment screw 60 threadably penetrating the same and bearing against the brace bar 57 to adjustably secure the brace 51 in the channel bar 53. It will be noted that due to the relation of the L-shaped bars 21, 22 and 23 to each other, the brace bar cannot extend in parallel relation to the longitudinal axis of the stringer assembly 20 and thus the loose connection between the channel bar 50 and the channel bar 53 is provided as shown in Figure 6 and heretofore described.

It will be noted that the brace bar 57 extends between and slidably penetrates the channel bar 53 associated with the vertical legs of each of the L-shaped bars 21 and 22 and the upper end of the brace bar 57 has welded thereto a cuff member 62 which is adapted to slidably receive the lower end of another of the brace bars 57 in the event that there are to be more than one intermediate L-shaped member 22, as would be the case in the event that the steps were to have more than two risers. The cuff member 62 is threadably penetrated by a set screw 63 which engages and secures the lower end of the second bar 57 to the first bar 57.

Referring to Figures 3 and 4, it may be noted that the angularly cut bottom 46 on the guide blocks 27 allows for adjustment of the vertically disposed channel bar 43 in such a manner as to provide a space between the upper edges of the form riser members 31 and 35 and the lower edges of the intermediate and upper L-shaped bars 22 and 23, respectively, thus leaving a space for passage of the mason's trowel therethrough in finishing the top surface of the treads of the steps over which they are disposed.

If this apparatus is used to pour steps up to a landing 17, no rear wall would be required, but if used where no landing is present, then a suitable rear wall would be required.

It is to be understood that as many sets of right angular members and associated parts as desired may be used to suit the number of steps required in each instance.

Also, even though, members 10, 11, 12, 13, 14, 15, 31 and 35 are shaded for wood in some of the figures of the drawings, it is to be understood that these parts may be fibre board, metal, plastic, or any other suitable material.

It is thus seen that I have perfected a stringer for use in combination with the forms used in pouring concrete steps, which is simple in construction and which comprises a plurality of L-shaped members to which the riser form members may be secured, and which may be adjusted with respect to each other in such a manner as to accommodate any size of tread or rise in the pouring of concrete steps. Another feature of this invention is that it may be assembled or disassembled with a minimum of tools and may be stored, when not in use, in a very limited space.

In the drawings and specification there has been set forth a preferred embodiment of the invention, and although specific terms are employed, they are used in a generic and descriptive sense only, and not for purposes of limitation,

the scope of the invention being defined in the claims.

I claim:

1. A stringer for supporting riser form members against which concrete is poured in the forming of concrete steps comprising upper and lower transverse frame members disposed at the landing of and at the foot of the steps, respectively, guide blocks secured to the uppermost of the frame members and to the vertical outer surfaces of each of the risers, a plurality of L-shaped members each having a horizontal leg and a vertical leg, the vertical legs of which slidably penetrate the guide blocks, clamping means associated with the guide blocks for clamping the vertical legs of the L-shaped members and guide blocks in fixed relation to each other, said L-shaped members comprising intermediate L-shaped members, an upper L-shaped member and a lower L-shaped member, a portion of the horizontal legs of the L-shaped members being disposed adjacent the vertical legs of the next adjacent L-shaped members, means associated with the vertical legs of the L-shaped members for securing the horizontal legs of the adjacent L-shaped members thereto.
2. In a form against which concrete is poured in the forming of concrete steps comprising end wall members and transverse frame members and riser members, lower, upper and intermediate L-shaped members, each of the L-shaped members having a horizontal and a vertical leg, guide blocks secured to each of said riser members and said transverse frame members, means for adjustably securing the horizontal leg of the lower L-shaped member in the guide block on one of the transverse frame members and means for securing the vertical leg of the upper L-shaped member in the guide block on another of the transverse frame members, means for adjustably securing the vertical legs of the lower and the intermediate L-shaped members in the guide blocks on the adjacent riser members, and means for adjustably securing the horizontal legs of the intermediate and the upper L-shaped members to the adjacent vertical legs of the lower and intermediate L-shaped members.
3. In a form against which concrete is poured in the forming of concrete steps comprising end wall members and transverse frame members and riser members, lower, upper and intermediate L-shaped members, each of the L-shaped members having a horizontal and a vertical leg, means for adjustably securing the horizontal leg of the lower L-shaped member to one of the transverse frame members and means for securing the vertical leg of the upper L-shaped member to another of the transverse frame members, means for adjustably securing the vertical legs of the lower and the intermediate L-shaped members to adjacent riser members, and means for adjustably securing the horizontal legs of the intermediate and the upper L-shaped members to the adjacent vertical legs of the lower and intermediate L-shaped members, said means for adjustably securing the horizontal legs of the intermediate and upper L-shaped members to the adjacent vertical legs of the lower and intermediate L-shaped members comprising a tubular member adjustably mounted on the vertical legs of each of the intermediate L-shaped members and the lower L-shaped member, a horizontally disposed tubular member connected to the vertically disposed tubular member adjacent its lower 75 end for slidably receiving the adjacent horizon-

tal legs of the intermediate and upper L-shaped members, locking means associated with the vertically disposed and horizontally disposed tubular members for adjustably securing the horizontal and vertical legs of adjacent L-shaped members in predetermined relation to each other.

4. In a form against which concrete is poured in the forming of concrete steps comprising end wall members and transverse frame members and riser members, lower, upper and intermediate L-shaped members, each of the L-shaped members having a horizontal and a vertical leg, means for adjustably securing the horizontal leg of the lower L-shaped member to one of the transverse frame members and means for securing the vertical leg of the upper L-shaped member to another of the transverse frame members, means for adjustably securing the vertical legs of the lower and the intermediate L-shaped members to adjacent riser members, and means for adjustably securing the horizontal legs of the intermediate and the upper L-shaped members to the adjacent vertical legs of the lower and intermediate L-shaped members, said means for adjustably securing the horizontal legs of the intermediate and upper L-shaped members to the adjacent vertical legs of the lower and intermediate L-shaped members comprising a tubular member adjustably mounted on the vertical legs of each of the intermediate L-shaped members and the lower L-shaped member, a horizontally disposed tubular member connected to the vertically disposed tubular member adjacent its lower end for slidably receiving the adjacent horizontal legs of the intermediate and upper L-shaped members, locking means associated with the vertically disposed and horizontally disposed tubular members for adjustably securing the horizontal and vertical legs of adjacent L-shaped members in predetermined relation to each other, a diagonally disposed brace member extending from the upper end of each of the vertically disposed tubular members, to one end of its associated horizontally disposed tubular member, a tubular member pivotally connected to the diagonally disposed brace member, a diagonally disposed brace bar extending from adjacent the vertical leg of the lower L-shaped member past and adjacent the vertical leg of each of the intermediate L-shaped members and slidably penetrating each of the tubular members which is pivotally connected to the diagonally disposed bar and means for locking the diagonally disposed brace bar in the tubular members through which it extends.

5. In a form against which concrete is poured in the forming of concrete steps comprising end wall members and transverse frame members and riser members, lower, upper and intermediate

L-shaped members, each of the L-shaped members having a horizontal and a vertical leg, means for adjustably securing the horizontal leg of the lower L-shaped member to one of the transverse frame members and means for securing the vertical leg of the upper L-shaped member to another of the transverse frame members, means for adjustably securing the vertical leg of the lower and the intermediate L-shaped members to adjacent riser members, and means for adjustably securing the horizontal legs of the intermediate and the upper L-shaped members to the adjacent vertical legs of the lower and intermediate L-shaped members, said means for adjustably securing the horizontal legs of the intermediate and upper L-shaped members to the adjacent vertical legs of the lower and intermediate L-shaped members comprising a tubular member adjustably mounted on the vertical legs of each of the intermediate L-shaped members and the lower L-shaped member, a horizontally disposed tubular member connected to the vertically disposed tubular member adjacent its lower end for slidably receiving the adjacent horizontal legs of the intermediate and upper L-shaped members, locking means associated with the vertically disposed and horizontally disposed tubular members for adjustably securing the horizontal and vertical legs of adjacent L-shaped members in predetermined relation to each other, a diagonally disposed brace member extending from the upper end of each of the vertically disposed tubular members, to one end of its associated horizontally disposed tubular member, a tubular member pivotally connected to the diagonally disposed brace member, a diagonally disposed brace bar extending from adjacent the vertical leg of the lower L-shaped member past and adjacent the vertical leg of each of the intermediate L-shaped members and slidably penetrating each of the tubular members which is pivotally connected to the diagonally disposed bar and means for locking the diagonally disposed brace bar in the tubular members through which it extends, a cuff member integral with the upper end of the diagonally disposed brace bar for receiving the lower end of a second brace bar disposed in alignment with the first brace bar and means for locking the lower end of the second brace bar in the cuff member.
